LENS-BLANK MANUFACTURE.

1,157,470.

Specification of Letters Patent.

Patented Oct. 19, 1915.

Application filed August 25, 1913. Serial No. 786,580.

To all whom it may concern:

Be it known that I, EDWARD A. VORNHOLT, a citizen of the United States, residing at Toledo, Lucas county, Ohio, have invented 5 new and useful Lens-Blank Manufacture, of which the following is a specification.

This invention relates to the manufacture of fused bifocal lenses, the object being to prevent the entrapping of air and foreign 10 particles between the welded surfaces of the assembled minor and major blanks of which the bifocal blank is composed.

In carrying out the invention, I aim to insure that the minor blank will break down 15 progressively from one edge to the other under the action of the heat and thereby insure that all of the air between the abutting surfaces will be forced out. To accomplish this, I use a clamp or pressure device 20 which bears upon the outer surface and edge of the minor lens blank, which causes said blank to tilt and be held in this tilted position in contact, at one point only, with the major blank, the outer or free end of the 25 tilted blank being thus without support. The weight of the blank serves to bend it as soon as softened under the action of the heat, at or near the one point of support, and the blank continues to drop from that 30 point diametrically until it finally closes down and unites with the major blank, the gradual bending of the minor lens insuring that all of the air between the surfaces of the blanks will be expelled before they come together. Another advantage afforded by thus 35 supporting the minor blank at one point in tilted relation with the major blank, is that a blast or current of air can more readily be directed between the abutting spaced-apart 40 surfaces immediately before the assembled blanks are placed in the furnace, to remove foreign particles, such as dust, which might have become lodged between the members.

Referring to the drawings: Figure 1 is a 45 section through a pair of lens elements clasped on a block showing an embodiment of features of the invention; Fig. 2 is a plan view of the elements of Fig. 1; Fig. 3 is a 50 view similar to Fig. 1 showing the way foreign matter may be removed from between the clasped lens elements; Fig. 4 is a section through the lens elements and supporting block, after fusing, in the union of the lens elements inside the housing or protecting 55 cover; Fig. 5 is a section through the fin-

ished lens; Fig. 6 is a showing of a pair of lens elements and a holding clamp therefor, said lens elements being plane instead of toric, as is the showing in Fig. 1; Fig. 7 is a plan view of lens elements shown in clasped relation, the clasp being disposed differently from the showing in Figs. 1 and 6; Fig. 8 is a view looking from the clasped side toward a pair of lens elements clasped on a block, said block having a slotted seat for 60 the clasp or clamp; Fig. 9 is a showing of a different form of seat in a block for clasping lens-elements for fusing into a bifocal lens blank; and Fig. 10 is a section through 65 a pair of lens elements for a bifocal lens resting upon a supporting block, the clamp for the lens elements in this instance engaging the lens elements only and not clamping the elements to the block.

The primary lens element 1 (Fig. 1) has 70 the seat 2 of concave form ground therein to provide a face. The secondary lens element 3 is provided with an opposing face 4. In this instance the secondary lens element 75 3 has in addition to the face 4 a seat or flattened portion 5. The clamp 6, say of spring metal, may have its extensions 7 drawn together so that in the positioning of the primary lens blank 1 and the secondary lens blank 3 with respective opposing faces 2 and 80 4 in position, the clamp may clasp or engage the outer face of the secondary lens blank 3 and force its seat 5 against the primary lens blank 1 by the second leg of the clamp 6 85 entering the recess or seat 8 in the supporting block 9 for the primary lens blank 1. As thus clamped in position the primary and secondary lens blank elements may be disposed in the desired position for fusing, the clamp positively holding the elements in 90 contact relation, the tilting being effected by the blanks themselves as acting upon each other from the clamped contacting portion. This contacting portion is local, and as 95 shown, away from the more used central portion of the opposing seats 2, 4, thereby leaving this most used region clear for the action of a dirt removing means as a suction nozzle 10, Fig. 3. Accordingly, without disturbance of the properly seated primary and secondary lens elements after the handling thereof, any foreign matter may be conveniently and readily removed and blanks may at once be mounted on the block 11 and covered by the housing 12 to insure the continu- 100 105 110

5 ance of the cleaned relation so that when the fusing follows to cause the secondary lens element 3 to become the fused secondary element 13 in union with the primary lens element blank 1, no foreign matter whatever may be entrained therein and there may be an absolute insurance against defect in the used region of the union.

10 There may in some instances be perceptible the initial contacting relation but this is so far removed from the generally used portion of the blank as to not interfere therewith and the entire area of the primary blank and of the secondary blank are accordingly acceptable for commercial uses in an article of such high standard as to be superior to the run generally found in practice at the present time. This great superiority in high percentage production is a commercial 15 feature enhancing the value of the devices herein disclosed which are simple for general adaptation. The fusing of element 13 into union with the primary lens element 1 is followed by a grinding of these parts into 20 the finished lens 14, 15 of Fig. 5.

25 Instead of forming the contacting seat in the secondary lens element, the end may be accomplished in a different manner as shown in Fig. 6, wherein the primary lens element 16 provided with a seat 17 has the opposing secondary lens element 18 with its face 19. This element 18 contacts at the cut away or seat portion 20 in the primary element 16 and is held in this position by the clamp 21 30 coacting in the ledge 22 of the block 23. The clamping has been shown as occurring at the outer edges of the primary and secondary lens elements and in most instances for convenience and economy such location 35 is desirable.

40 In the showing in Fig. 7 the clamp 24 in the block 25 reaches over the edge of the primary blank element 26 to hold in contacting relation an edge of the secondary blank 27 away from the edge of the primary blank 26 which effects a tilting relation but not from an edge point of each of the blank elements.

45 In Fig. 8 the block 28 is shown with an elongated recess 29 for the reception of the lower prong of the clamping member 30 which reaches over the near edge of the primary blank element 31 to hold the secondary blank element 32 in edge contact therewith and effect the tilting relation from an edge 50 of each of said blank elements.

55 In Fig. 9 the block support 33 is shown with its opening 34 for receiving the clamping member, said opening being of large 60 width and of short extent.

65 In Fig. 10 the fuse block support 35 with a recess or seat 36 for the clasp or clamping device 37 coacts with the primary lens element blank 38 having the plane seat 39 opposing which is the secondary blank element

40 having a curved opposing seat 41. In this instance as in some others a secondary seating face is not established to bring about the tilting relation by the holding clamp and still the holding clamp may be effective for 70 local engagement. Again in this instance the clamp clasps only the lens elements to hold them in the desired opposed relation and does not clamp them to the fuse block. In this positive holding by clasping of the primary and secondary lens elements in position the initial contact point is a minimum and after the fusing the ready removal of the holding means leaves no mark whatever upon the blank which is then ready for 75 grinding. This means that when the primary lens element is to finish for a 25 m. m. disk, a disk of that size may be used initially, a feature meaning very considerable saving in labor and material,—in labor that 80 the smaller disk may be prepared more cheaply and in material in that all of the material is used with no waste. The clasp or clamp may or may not be of resilient material, the feature being to engage for 85 tilting the elements and for the fusing the clamp may be of a character that it may be discarded. Again, in this character of secondary lens element, there is in the combination a regular continued departure from 90 the seating or contact position and the melting down temperature for fusing may be a minimum in that there is no obstruction or abrupt lines to be overcome in the fusing of this secondary disk. This is an economy 95 in heating or fusion which extends still further in that it keeps the lower melting point secondary element farther away in temperature from the fusing point of the more refractory primary lens element, thus insuring 100 retention of the initial seat form as given to the primary lens element. With this insurance of the initial seat form, more delicate and accurate results with a high 105 percentage of the commercial output is obtained.

110 To further contribute to the utility herein, there is considerable added value in the low temperature at which fusing may be effected, for as this heat is not sufficient to distort the seat in the major lens element of crown glass as the minor lens element of flint glass is uniting therewith, there is not sufficient softening of the crown glass to adhere to the support or block, and roughening 115 from this source is totally avoided and chalking to prevent sticking thus is eliminated and dust therefrom avoided. This added cleanliness precludes accidental dust 120 defects in the fused articles.

125 What is claimed and it is desired to secure by Letters Patent is:

130 1. The process of making blanks for bifocal lenses consisting in forming a seat in one lens element, holding a second lens ele-

ment in tilted relation to said seat by pressure upon the edge of the second element and then subjecting the two elements to heat until the second element has settled into the seat in the first element.

2. The process of making blanks for bi-focal lenses consisting in forming a seat in one lens element, supporting a second lens element at one point only adjacent to said seat and subjecting the elements to heat until the second element breaks down and rests throughout its face in contact with said seat.

3. The process of making blanks for bi-focal lenses which consists in forming a seat in one lens element, placing a second lens element over said seat, holding the second element in a tilted position by pressure upon one edge thereof and subjecting the assembled elements to heat until the second ele-

ment has settled into the seat in the first 20 element.

4. The process of making blanks for bi-focal lenses consisting in forming a curved cavity in one lens element, forming a convex face on a second lens element, pressing 25 the two elements together at one point of contact adjacent the edge of said cavity and thereby tilting one element with respect to the other and subjecting the elements to heat while thus held until the second element falls into and fills the cavity in the first element.

In testimony whereof I hereunto set my hand in the presence of two witnesses.

EDWARD A. VORNHOLT.
